MORITZ C. BOESCH, OF PERTH AMBOY, NEW JERSEY.

CIGAR-CUTTING MACHINE.

1,321,591.

Specification of Letters Patent. Patented Nov. 11, 1919.

Application filed April 7, 1919. Serial No. 287,985.

To all whom it may concern:

Be it known that I, MORITZ C. BOESCH, a citizen of Germany, and a resident of the city of Perth Amboy, in the county of Middlesex and State of New Jersey, have invented certain new and useful Improvements in Cigar-Cutting Machines, of which the following is a specification.

This invention relates to certain improvements in the construction of cigar cutting machines and particularly to that class of such machines which is used by cigar makers to cut freshly made cigars to uniform length, by means of an adjustable gage, which by its predetermined distance from a pair of shearing cutters fixes the length of the cigars to be trimmed.

The objects of my improvement are to provide an instrument for the cigar maker which can quickly and exactly be adjusted to cut cigars of required length and whose adjustment and cutting qualities are not disarranged by continuous and severe use.

With this and other objects in view, the invention consists in certain novel details of construction and arrangements of parts hereinafter described and shown and illustrated in the accompanying drawings, made part of these specifications, in which:

30 Figure 1 is a front elevation of the machine, showing a part of the base broken away.

Fig. 2 is a plan view of Fig. 1.

Fig. 3 is a side elevation of the machine, as seen from the left side of Figs. 1 or 2.

Fig. 4 is a section of the machine on the line 4—4 of Fig. 1.

Similar characters of reference indicate corresponding parts throughout the various views.

My cigar cutting machine is preferably constructed as follows:

The base plate 1 is provided with a longitudinal groove 1^a in its upper face, which accommodates the cigar to be trimmed, and extends over the full length of base 1, for a part of its length it is provided with a slot 2, which is widened out at the end 2^a. The lower part of the base 1 is preferably hollow (as shown in Fig. 4.) and closed at its ends by the transverse walls 1^b and 1^c. Slot 22 accommodates a longitudinal screw or spindle 3 provided with a head 3^a and a fixed collar 3^c leaving a circular groove

between them, which fits into a slot of side wall 1^b and holds spindle 3 in rotatable, but longitudinally fixed position within slot 2.

A gage 4 consists of a vertical plate, whose gaging face 4^a is arranged transversely to groove 1^a and whose sides are formed to fit this groove. The lower narrow part of gage 4 forms a nut 4^b for spindle 3 on which the gage travels when the spindle is rotated. An aperture 3^e in head 3^a carries loosely a ring 5 acting as a handle for spindle 3. This ring is formed into such shape that its flat part 5^a rests on any surface S which supports the machine, when aperture 3^e is in parallel alignment with said surface.

The stationary, lower knife blade 6 is provided with a semicircular cutting edge, and fastened to the end plate 1^c of the base, by means of bolts 6^a. The upper, movable knife blade 7 is held on the transverse leg 8^a of lever 8, whose main part runs parallel to groove 1^a along the rear longitudinal edge of base 1 and is pivoted to a boss 9 of said base, located near the end plate 1^b, by means of pivot screw 10. Lever 8 and with it knife 7 are operated by pressing the finger plate 8^b attached to knife holder 8^a. A torsional spring 11 which preferably encircles boss 9 tends to open lever 8 and knife 7. The cutting faces of knives 6 and 7 are ground cylindrical, about an axis formed by the pivot screw 10. A slightly resilient arm 12, preferably attached to knife 6 extends in vertically upward direction from the base and serves as a guide against transverse motion for the extreme forward end of lever 8, while the hook 12^a at the upper end of the guide arm 12 limits the upward motion of lever 8.

While the operation of trimming cigars to uniform length on this machine does not differ materially from that on other machines, the facility of its setting for use and the reliability of its cutting-action are greatly improved by the present invention.

In machines at present in use, the gage is shifted in a slot or on a rod, to the desired position, which is at best approximate, and then clamped in that place. If the gage remains in the same place for a long time, it generally gets rusted in tightly and can only be loosened and shifted with difficulty.

If however the clamp is not drawn very tight, the gage shifts frequently by the vibration of cutting.

In my machine the gage is not clamped 5 to the groove 1^a or slot 2, but held in place by spindle 3, it may be gradually adjusted thereby to any desired position and held in place at every one half turn of the spindle 3 by means of handle-ring 5 whose flat portion 5^a falls against the supporting surface of the machine, by its own weight and prevents any incidental movement of the gage. The gage 4 and spindle 3 can readily be lifted out of the machine for cleaning 15 purposes and their rusting together prevented without disturbing the position of the gage on the spindle, and thereby preserving the setting of the machine for a certain length of cigar, while vibration does 20 not disturb the position of the gage.

The arrangement of the upper cutting knife, to swing about a pivot whose axis is parallel to the cutting faces of the knives, instead of about a pivot whose axis is transverse thereto, which is the old construction, insures a permanent relation of the cutting faces of the knives, as the loosening of the pivot screw does not affect the tightness of the cutting faces of the knives against each other; in fact the head of the pivot screw 30 may loosely lean against lever 8 in my machine, and the operator is relieved of the constant attention to be given to the cutting knives and of pressing them against each other by hand, which is usually the case in machines heretofore used, when the pivot screw loosens by friction against its head. An additional safeguard for reliable cutting-action is provided by the upright guide 35 12 which presses constantly and evenly against the lever 8 and thereby holds the cutting faces together. By means of the considerable length of lever 8 in my machine the angle of motion on the pivot screw 40 for the same opening of the knives is reduced, which tends to reduce the chance of loosening the pivot screw.

Having thus described my invention, what I claim as new and desire to secure by Letters Patent is:

1. In a device of the kind described, a support to hold a cigar, a shaped knife at one end thereof, a threaded spindle, extending longitudinally of said support near the opposite end, a gage in threaded engagement with said spindle, and means holding said spindle slidably connected to said support to permit its instant removal.

2. In a device of the kind described, a support, a longitudinal groove thereon to hold a cigar, a cutter at one transverse end of said support, a gage slidable lengthwise of said support and a screw, arranged parallel to said groove, and holding means, permitting the removal of said screw from said

support, perpendicularly to its axis and independently of the position of said gage.

3. In a device of the kind described, a support, to hold a cigar, a shaped knife at one end thereof, a screw, rotatably held at 70 the opposite end thereof, a gage movable by said screw toward and away from said knife and automatic means preventing rotation of said screw to lock said gage at selective distances from said knife. 75

4. In a device of the kind described, a support to hold a cigar, a cutter at one end thereof, a gage slidable lengthwise thereof, means to gradually vary the distance between said gage and said cutter, and automatic locking means adapted to arrest said gage in uniformly varying spacings from said cutter. 80

5. In a device of the kind described, a support to hold a cigar, a cutter at one transverse end thereof, a rotatable spindle, extending lengthwise of said support, a gage in threaded engagement with said spindle, and self-acting means on said spindle adapted to prevent its rotation and to lock 90 said gage at selective distances from said cutter. 85

6. In a device of the kind described, a support to hold a cigar, a cutter at one end thereof, a gage, a screw adapted to move 95 said gage lengthwise of said support and locking means forming a handle for said screw, adapted to stop said movement in uniform intervals.

7. In a device of the kind described, a support to hold a cigar, a pair of shearing knives at one transverse end thereof, one of said knives being stationary and the other knife being oscillatable on an axis arranged transversely to said support. 100

8. In a device of the kind described, a support to hold a cigar, a stationary knife at one transverse end thereof, an oscillating knife, pivotally held at the opposite transverse end thereof, to coöperate with said stationary knife, and a gage, adjustable longitudinally of said support. 105

9. In a device of the kind described, a support to hold a cigar, a stationary knife at one transverse end thereof, an oscillating knife coöperating therewith, held on a knife-arm extending longitudinally of said support and a gage movable parallel to the plane of motion of said knife-arm. 115

10. In a device of the kind described, a support to hold a cigar, a pair of cutting knives at one transverse end thereof, one of said knives being held on an oscillating arm extending longitudinally of said support, and a guide slidably engaged by said arm to 120 prevent transverse motion of said arm. 125

11. In a device of the kind described, a support to hold a cigar, a stationary knife and an oscillating knife, forming a cutting couple at one transverse end thereof, an arm 130

holding said oscillating knife, extending longitudinally of said support, and means to guide said arm against transverse motion.

12. In a device of the kind described, a support to hold a cigar, a cutting couple, consisting of a stationary and an oscillating knife, at one transverse end of said support, said oscillating knife being pivoted on an

axis transverse to said support, a screw extending lengthwise of said support, held near the other transverse end of said support, a gage operated by said screw toward and away from said cutting couple, and means to lock said gage at uniformly varying distances from said cutting couple.
